US0D1037544S

(12) **United States Design Patent** (10) **Patent No.:** **US D1,037,544 S**
(45) **Date of Patent:** **** Jul. 30, 2024**

(54) **STRING LIGHT ATTACHMENT SYSTEM**

(71) Applicant: **Plymouth Hardware, LLC**, Grand Rapids, MI (US)

(72) Inventors: **Michael Carpenter**, Grand Rapids, MI (US); **Wayne Ludlum**, Fountain Valley, CA (US); **Hayden Lemire**, San Francisco, CA (US); **Jordan Nollman**, Cambridge, MA (US); **Rich Orsini**, Hyde Park, CA (US); **Matt Bettencourt**, Ludlow, MA (US); **Mark Henry Perez de Leon**, Cabuyao (PH)

(73) Assignee: **PLYMOUTH HARDWARE, LLC**, Grand Rapids, MI (US)

(**) Term: **15 Years**

(21) Appl. No.: **29/832,861**

(22) Filed: **Mar. 30, 2022**

(51) **LOC (14) Cl. 26-05**

(52) **U.S. Cl.**

USPC **D26/140**

(58) **Field of Classification Search**

USPC D26/23, 25, 26, 60, 67, 113, 138, 140,
D26/155

CPC F21S 4/10; F21V 19/0055; F21V 21/043

(57) **CLAIM**

The ornamental design for a string light attachment system, as shown and described.

DESCRIPTION

FIG. 1 is a top perspective view of a string light attachment system showing the claimed design;

FIG. 2 is a front view thereof;

FIG. 3 is a back view thereof;

FIG. 4 is a right view thereof;

FIG. 5 is a left view thereof;

FIG. 6 is a top view thereof;

FIG. 7 is a bottom view thereof; and,

FIG. 8 is a bottom perspective view thereof.

The broken lines in the drawings indicate portions of the string light attachment system that form no part of the claimed design.

1 Claim, 8 Drawing Sheets
